Primary Examiner — Bridget L Eland*(74) Attorney, Agent, or Firm* — Davis Wright Tremaine LLP; Heather M. Colburn(57) **CLAIM**

The ornamental design for a smartphone, as shown and described.

DESCRIPTION

FIG. 1 is a front perspective view of a smartphone showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof; and,

FIG. 8 is a bottom plan view thereof.

The broken lines immediately adjacent the features shown in continuous lines in FIGS. 1-8 represent the bounds of the claimed design, while all other broken lines are directed to environment and are for illustrative purposes only; the broken lines form no part of the claimed design.

1 Claim, 6 Drawing Sheets(56)
